DESIGN FOR AN ELECTRIC CLOCK

Joseph Gottlieb, Jersey City, N. J.

Application November 21, 1938, Serial No. 81,260

Term of patent 7 years

To all whom it may concern:

Be it known that I, Joseph Gottlieb, a citizen of the United States, residing at 403 Communipaw Avenue, Jersey City, in the county of Hudson, State of New Jersey, have invented a new, original, and ornamental Design for an Electric Clock, of which the following is a specification, reference being had to the accompanying drawing, forming part thereof.

The figure is an elevational view of a clock showing my new design and the dominant feature

of said design is the provision of a base including disc portions spaced apart by a pedestal ornamented with columns, said base supporting a globe, there being provided intermediate said base and said globe, an annular clock dial.

The appearance of the base is exactly the same on the side opposite that shown in the drawing.

I claim:

The ornamental design for an electric clock as shown and described.

JOSEPH GOTTLIEB.
